UNITED STATES PATENT OFFICE

ESTAFIY TEMENS, OF ELIZABETH, NEW JERSEY

AEROPLANE BOAT

Application filed March 6, 1929. Serial No. 344,760.

This invention relates generally to flying machines and has more particular reference to a novel device arranged for flying or for motion upon water.

5 The invention has for an object the provision of a device of the class mentioned, which is of simple durable construction, desirable in use and efficient in action, and which can be manufactured and sold at a reasonable 10 cost.

The invention proposes the use of a bottom ship portion connected with a deck house and side horizontal wings. These wings are provided with rail around their edges, and an 15 elevator tail wing is connected at the rear of these wings. A fixed stabilizer wing and a movable steering wing are supported from the rear of the deck house. A plurality of prime movers are mounted on the device and 20 consist of gas and electric motors, and are provided with suitable propellers for propelling the device.

For further comprehension of the invention and of the objects and advantages there- 25 of, reference will be had to the following description and accompanying drawings, and to the appended claims in which the various novel features of the invention are more particularly set forth.

30 In the accompanying drawing forming a material part of this disclosure:—

Fig. 1 is a perspective view of a device constructed according to this invention.

Fig. 2 is another perspective view of the 35 device seen from the lower side thereof.

Fig. 3 is a front elevational view of the device.

Fig. 4 is a side elevational view of the device constructed according to modified form.

40 Fig. 5 is a fragmentary vertical sectional view of a portion of Fig. 4.

Fig. 6 is an enlarged detail plan view of the elements used in mounting the motors of the device.

45 Fig. 7 is a fragmentary vertical sectional view, taken on the line 7—7 of Fig. 6.

Fig. 8 is a front elevational view of a device constructed according to modified form.

50 Fig. 9 is a front elevational view of another

device constructed according to modified form.

The reference numeral 10 indicates generally the ship portion of a device having a bow 11 and a keel 12. A deck house 13 is mounted on the top of the ship portion and side wings 14 and 15 extend horizontally and are connected with the deck house. Railings 16 are mounted along the edges of the wings 14 and 15. The deck house is provided with a plurality of windows 17, and the ship portion is provided with a plurality of glass enclosed port holes 18.

The ship portion is also provided with an entrance door 19 for engagement over a door opening 20 and a ladder 21 extends downwards from this door opening. A driving means 22 is mounted within the ship portion 10 and connects with a water propeller 23 for propelling the device thru water. An elevator tail wing 24 is connected on the rear ends of the wings 14 and 15 and a fixed stabilizer wing 25 is attached by brackets 26 onto the rear side of the deck house 13. A steering wing 27 is mounted on the rear edge of the fixed stabilizer wing 25.

A cabin 28 for shielding the pilot is mounted upon the deck house 13. The roof of the deck house indicated by numeral 29 is slidably arranged on the sides of the deck house by clips 30 connected with the sides and acting against the edges of the roof. When this roof is moved backwards the front portion of the deck house is opened for permitting the entrance of air. The dot and dash lines 31 in Fig. 5 disclose the rearward position of the roof.

Combination gas and electric motors 32 are mounted upon the top side of the side wings 14 and 15 at the rear edge thereof and are provided with propellers 33. These motors are attached on bases 34 connected with blocks 35 as hereinafter further described.

The roof 29 is provided with sections 36 hingedly connected at their rear ends as at 37 and having their front ends adjustable by means of brackets 38 connected therewith and engaging upon screws 39 supported from the roof 29. Nuts 40 engage upon the screws on

the top and bottom sides of the bracket for holding the sections 36 in desired positions. Combination gas and electric motors 41 are mounted upon these sections 36 and are provided with propellers 42. These motors are attached on bases 34 connected with blocks 35 as hereinafter further described. A plurality of combination gas and electric motors 43 are mounted on the lower sides of the 10 wings 14 and 15 and are provided with propellers 44. These motors are attached on bases 34 connected with blocks 35 and herein-after further described.

In the modified form of the device illustrated in Fig. 4 a landing gear 45 has been shown attached to the bottom of the device. A ladder 46 has been shown connected in front of the device and at its top end upon the deck house 13. The ship portion 10 is 20 divided by partitions 45^a into an upper and lower chamber 46^a and 47, respectively. Stairs 48 connect the lower chamber with the upper chamber and stairs 49 connect the upper chamber with the deck house.

25 The bases 34 are provided with inclined sides 50, and at the point of meeting of these inclined sides the bases are pivotally connected with blocks 35 as indicated by numeral 51. These blocks are provided with 30 slots 52 thru which wedge members 53 project and engage against the inclined sides 50 on opposite sides of the pivot point 51. Screws 54 rotatively engage within the blocks 35 and threadedly engage the wedge members 53 for advancing or retracting the same relative to the pivot point 51. These screws 35 are provided with square ends 55 for engagement by turning tools. The square ends of the screws may be rotated for advancing 40 the wedges in one direction for pivoting the base 34 in that direction or for advancing the wedges in the opposite direction for pivoting the same base in the opposite direction about the pivot 51. It is pointed out that 45 this arrangement permits the adjustment of the position of the various motors for directing the propellers in the most advantageous directions.

In the modified form of the device illustrated in Fig. 8 a large deck house 56 has 50 been illustrated connected on the ship portion 57. Brackets 58 connect with the sides of the ship portion 57 and pivotally support the motors 59 provided with the propellers 60. These motors are provided with bases 34 engaged with the blocks 35 as before described for permitting a pivoting of the motors in desirable direction. Top motors 61 and 62 are shown mounted upon the deck 55 house 56 and are provided with bases 34 engaged with the blocks 35 as before described. Side wings 63 are shown connected with the sides of the deck house.

In the modified form of the device illustrated in Fig. 9, blocks 35 have been shown

attached on the sides of the ship portion 57 and motors 64 connect with these blocks as before described. Additional motors 65 are connected with blocks 35 which are attached by brackets 66 to the sides of the ship portion 57.

70 While I have shown and described the preferred embodiment of my invention, it is to be understood that I do not limit myself to the precise construction herein disclosed and the right is reserved to all changes and modifications coming within the scope of the invention as defined in the appended claims.

75 Having thus described my invention, what I claim as new, and desire to secure by United States Letters Patent is:—

80 1. In combination with a flying aeroplane-boat of the class described having a plurality of combination gas and electric motor driven propellers, a base supporting each of said combination prime movers and provided with inclined sides terminating at a point, a block attached on said aeroplane boat and pivotally supporting said base at said point, and a pair of wedge members adjustably mounted on said block and on opposite sides of said pivot point and engaging said inclined sides for holding the prime mover stationarily and upon adjustments changing the positions of said prime mover.

85 2. In combination with a flying aeroplane-boat of the class described having a plurality of combination gas and electric motor driven propellers, a base supporting each of said combination prime movers and provided with inclined sides terminating at a point, a block attached on said aeroplane boat and pivotally supporting said base at said point, and a pair of wedge members adjustably mounted on said block and on opposite sides of said pivot point and engaging said inclined sides for holding the prime mover stationarily and upon adjustments changing the positions of said prime mover, said wedge members being 90 slidably mounted on said block and threadedly engaging with screws rotatively mounted on the block and constituting said adjustable mounting.

95 In testimony whereof I have affixed my signature.
